SMOKING PIPE

Joseph Saulnier, Falmouth, Mass.

Application November 16, 1942, Serial No. 465,754

3 Claims. (Cl. 131—224)

This invention relates to smoking pipes.

An object of this invention is to provide an improved bowl for a pipe which includes a bottom part and an upper part, the latter being hinged to the bottom part.

Another object of this invention is to provide an improved bowl which is formed with an overhanging rim which will act to prevent the tobacco from spilling out of the bowl.

A further object of this invention is to provide an improved bowl which will permit insertion of the new tobacco from the bottom portion of the bowl, and which will facilitate cleaning of the bowl.

A further object of this invention is to provide an improved bowl including a hinged upper part and a lower part formed with a chamber in which a combined filter and moisture absorbing element is positioned.

With the foregoing objects and others which may hereinafter appear, the invention consists of the novel construction, combination and arrangement of parts as will be more specifically referred to and illustrated in the accompanying drawing, wherein is shown an embodiment of the invention, but it is to be understood that changes, variations and modifications may be resorted to which fall within the scope of the invention as claimed.

In the drawing:

Figure 1 is a detail top plan of a smoking pipe constructed according to an embodiment of this invention;

Figure 2 is a sectional view taken on the line 2—2 of Figure 1; and

Figure 3 is a sectional view taken on the line 3—3 of Figure 2.

Referring to the drawing, the numeral 10 designates generally a pipe bowl having a stem 11 carried by the lower portion thereof and a mouthpiece 13 is mounted in the inner portion of the stem 11. The stem 11 has a bore 12 extending therethrough which terminates at its forward end in a chamber 14 which is formed in the lower portion of the bowl 10.

The bowl 10 is formed of an upper part 15 and a lower bowl part 16. The two bowl members 15 and 16 are hingedly secured together by a hinge 17 which has one leaf 18 thereof secured by fastening means 19 to the lower end of the upper bowl member 15. The other leaf 20 of the hinge 17 is secured by fastening means 21 to the upper side of the lower bowl member 16.

The lower bowl member 16 is formed with a flat upper side 22 against which the flat lower

end 23 of the upper bowl member 15 is adapted to engage. In order to provide a means whereby the two bowl members 15 and 16 may be sealed relative to each other, I have provided a cylindrical member 24 which is secured by detents 25 in the lower bowl member 16. The sealing member 24 is an inner sealing member, and has a portion thereof projecting downwardly into an opening 26 which is formed in the lower bowl member 16. A substantial portion of the lower inner member 24 extends upwardly above the upper side 22 of the lower member 16 and is adapted to telescopingly engage within a cylindrical ring or upper sealing member 27. The upper sealing member 27 is mounted in a recess 28 which is formed in the lower portion of the upper bowl member 15 and is firmly secured within the recess 28 by means of detents 29. The part 27 has a fairly loose fit over part 24 the fit being just tight enough to prevent any tobacco particles from leaking out of the bowl. It will be understood that while this may be a sealing fit as to tobacco it is not a liquid-tight seal and there will be a very slight space between elements 24 and 27.

A combined filter and moisture absorbing element 30 is mounted in the bottom portion 16 and may be formed of any suitable fibrous filtering means which will permit the smoke to pass from the interior of the bowl 10 to the passage 12.

The filtering member 30 is formed of moisture absorbing material, so as to absorb the moisture which accumulates in the bottom of the bowl 10.

The upper bowl member 15 has mounted in a recess 31, formed in the upper end thereof, a cylindrical member 32. The cylindrical member 32 is secured in the recess 31 by means of detents 33, and the cylindrical member 32 is formed with an inwardly projecting annular flange 34 which provides a restricted opening in the upper end of the upper bowl member 15. The flange 34 is substantially flush with the upper side 35 of the upper bowl member 15, and the opening 36 formed by the flange 34 is sufficiently small to prevent the unburned tobacco, and also ashes from the burned tobacco, from dropping out of the bowl when the pipe is laid on its side.

In the use of this pipe the upper bowl member 15 is adapted to be swung upwardly and inwardly in order to fill the bowl, the unburned tobacco being inserted into the upper bowl member 15 from the bottom thereof. The flange 34 will provide a means whereby the tobacco will be held against outward movement at the upper end of

the bowl 10, and when the upper bowl member 15 has been filled it may be swung downwardly to a closed position which is the position shown in Figure 2. In this position the two annular members 24 and 27 will be in telescoping position and will seal the lower portion of the bowl. In order to prevent the tobacco from being pushed out of or dropped through the opening 36 when the part 15 is being filled, the finger of the user is held over the opening 36 while the pipe is being filled, as is customary with pipe smokers in filling their pipes.

The combined filtering and moisture absorbing material 30 will filter the smoke being drawn toward the passage 12 and will also absorb any moisture accumulating in the bottom portion of the bowl.

With a pipe of this kind it is an easy matter to not only fill the pipe bowl in such a manner that the tobacco will not drop out, but it is also an easy matter to clean the bowl after it has been in use.

The structure herein disclosed also provides a means to economize on tobacco by reason of the fact that in refilling, the unburned tobacco remaining in the bowl is pushed upward with fresh tobacco to the top of the bowl. This structure also provides a continuous process of refilling and smoking as it provides a means to refill the bowl from the bottom while the tobacco is burning.

I claim:

1. In combination a pipe a bowl formed of an upper hinged portion and a lower portion, said bowl having an overhanging rim, a stem having a bore extending therethrough carried by said lower portion, a mouthpiece mounted in the inner portion of said stem, said bore terminating at its forward end in a chamber formed in said lower portion, said lower bowl portion having a flat upper side, said upper hinged portion having a flat lower end adapted to engage therewith, a cylindrical sealing member secured by detents in the lower bowl, a portion of said sealing member projecting downwardly into an opening in said lower bowl, and a portion of said sealing member extending upwardly above the upper side of the lower member and adapted to telescopingly engage within a cylindrical ring or upper sealing

member, said upper sealing member being mounted in a recess formed in the lower portion of the upper bowl, and being secured within the recess by means of detents, and a combined filter and moisture absorbing element mounted in the bottom portion.

2. A tobacco pipe having a bowl formed of upper and lower sections hingedly connected together, means whereby said sections may be sealed relative to each other, and means whereby tobacco contained in said pipe may be retained therein when the two sections are separated said latter means including a cylindrical member tightly fitting into the upper end of said bowl, and an inwardly projecting flange integral with said cylindrical member and forming a tobacco retaining means.

3. In combination a pipe, a bowl formed of an upper hinged portion and a lower portion, said bowl having an overhanging rim, a stem having a bore extending therethrough carried by said lower portion, a mouthpiece mounted in the inner portion of said stem, said bore terminating at its forward end in a chamber formed in said lower portion, said lower bowl portion having a flat upper side, said upper hinged portion having a flat lower end adapted to engage therewith, a cylindrical member secured by detents in the lower bowl, a portion of said cylindrical member projecting downwardly into an opening in said lower bowl, and a portion of said cylindrical member extending upwardly above the upper side of the lower member and adapted to telescopingly engage within a cylindrical ring member, said cylindrical ring member being mounted in a recess formed in the lower portion of the upper bowl and being secured within the recess by means of detents, a combined filter and moisture absorbing element mounted in the bottom portion, and a cylindrical member formed with an inwardly projecting flange providing a restricted opening mounted in the upper end of the upper bowl member, said flange being substantially flush with the upper side of the upper bowl member thereby forming an opening sufficiently small to prevent unburned tobacco from dropping out of the bowl of the pipe when laid on its side.

JOSEPH SAULNIER.
